UNITED STATES PATENT OFFICE.

EMIL JAGENBERG, OF DUSSELDORF, GERMANY.

BAG-FILLING MACHINE.

1,001,855.

Specification of Letters Patent. Patented Aug. 29, 1911.

Application filed October 21, 1910. Serial No. 588,249.

To all whom it may concern:

Be it known that I, EMIL JAGENBERG, a citizen of Germany, residing at Dusseldorf, Germany, have invented a new and Improved Bag-Filling Machine, of which the following is a specification.

This invention relates to a machine of novel construction adapted to fill measured quantities of mealy, granular or other substances into paper bags or similar receptacles.

The machine operates automatically, is of simple construction and thoroughly reliable.

In the accompanying drawing: Figure 1 is a side elevation of a machine embodying my invention; Fig. 2 a front view thereof; Fig. 3 a cross section on line A—B, Fig. 2; Fig. 4 a longitudinal section through the upper part of the machine on line C—D, Fig. 5; Fig. 5 a plan, and Fig. 6 a detail of a measuring vessel and adjoining parts with the gates and lower shells in section.

A movable carrier 1 shown to consist of a disk is by a hub firmly secured to a rotatable upright shaft 2. From the carrier depends a sleeve 3, stepped on a bearing 4 of the machine frame. Above the carrier is mounted a hopper 5 engaging a flanged collar 6, and adapted to contain the material to be filled into the bags. Collar 6 is arranged directly above the carrier, beneath which the latter is however free to rotate. The carrier is provided with a plurality of openings arranged at equal radial distances from its center and having depending tubular shells 7, which are successively advanced beneath collar 6 by the rotation of the carrier. Shells 7 are telescoped by lower shells 8 of a plate 9 which is secured to a sleeve 10. This sleeve encompasses sleeve 3 upon which it is axially slidably by a groove and feather connection 3^a, so that it will be taken along by the same. Shells 8 are at their bottoms closed by flap valves 11 and together with shells 7 constitute the measuring vessels, the size of which may be adjusted by vertically setting shells 8 as hereinafter described. To the spindles 12 of valves 11 are secured arms 13 connected by link 14. One of the spindles 12 of each shell further carries an arm 15, having roller 16, which moves over a glideway 17, against which it is held by a spring 18, said spring being suspended between corresponding lugs of arms 13.

At the point where the bag is to be

charged, is located beneath carrier 1, a funnel 19, and here glideway 17 has a notch 20. When a measuring vessel arrives over funnel 19, roller 16 of the arm 15 pertaining to such vessel is by spring 18 drawn into notch 20. In this way the valves are opened, so that the vessel which had been charged while below hopper 5, will now be emptied through funnel 19, into the bag to be filled. To shells 8 are secured deflectors 21 that prevent flour or similar material from spreading, when the valves are suddenly opened.

Between sleeve 10 and glideway 17 is fitted a rotatable ring 22 having a notch 22^a similar to that of the glideway and provided with a handle 23 that extends outwardly through a slot 23^a of said glideway. By turning ring 22 through handle 23, its notched section can be moved out of registry with notch 20, so that the rollers 16 that likewise engage ring 22, cannot enter the notch 20 and the valves will remain closed. In this way, the measuring apparatus may be put out of action without interrupting the movement of the carrier.

Glideway 17 is provided with lateral eyes 24 engaged by the upper ends of rods 25, the lower ends of which are guided in eyes 26 of the machine frame. Rods 25 are connected by a cross arm 27, carrying a pair of levers 32. These levers are connected by a rod 28 to which is pivoted a right hand screw 29 engaged by the threaded hub 30 of a hand wheel. An oppositely threaded section of this hub engages a left hand screw rod 31 pivoted to the machine frame, so that by turning the hand wheel, levers 32 can be tilted in either direction, so as to raise glideway 17 by rods 25. Glideway 17 extends under a collar 10^a of sleeve 10 and is supported upon a ring 34, so that sleeve 10 together with shells 8 will participate in the adjustment of the glideway. In this way the sizes of all the measuring vessels composed of shells 7 and 8 may be simultaneously changed. One of the rods 25 carries a pointer 47 moving along scale 48, so that the measuring devices may be readily set to any capacity desired.

Shaft 2, together with the carrier and the measuring vessels, is intermittently rotated from shaft 35. A cam 36 of the latter actuates a rod 37 to which is pivoted a pawl 38, that is spring-pressed into engagement with a notched disk 39. The shaft of disk

30 is by a chain drive 40 connected to a sprocket wheel 2* of shaft 2, the transmission being so proportioned that during each complete revolution of shaft 35, shaft 2 with 5 carrier 1, receives one quarter turn. To properly center the measuring vessels during this movement beneath hopper 5 or funnel 19, there is provided a detent 41 spring-pressed into engagement with notched disk 10 39. After fulfilling its function, detent 41 is retracted by shaft 35 through an eccentric and a rod 43 having a pin that engages an arm 41* of the detent. A second arm 44 of detent 41 bears against a roller 45, of 15 pawl 38. After a partial rotation of carrier 1 and when detent 41 engages a notch of disk 39, it will by arm 44 disengage pawl 38 from the disk, so that the pawl may freely return to its initial position. By this 20 construction, the notches of disk 39 may be made of a substantial depth, so that a positive action is insured.

To collar 6 is secured a curved finger or stripper 46 arranged with its central section 25 bent horizontally as shown in Fig. 5 and lying above the path of the measuring vessels, and thence extends toward the axis and the circumference of the carrier. Should any material drop by agitation or otherwise 30 from the measuring vessel upon the carrier, it is by the rotation of the latter, pushed into the path of the measuring vessels, and will fall into the empty vessel moving toward hopper 5.

35 Within hopper 5 is centered a shaft 50 journaled in bearing 51 and carrying a rope pulley 54. To the shaft is secured an upright wing 52 which tapers from top to bottom and extends from the top of the carrier to a point above the maximum filling 40 level of the hopper. Shaft 50 further carries a wire bail 53, having an inclined shank which extends snugly along the side of the hopper. During the rotation of shaft 50, 45 wing 52 will clear a central space within the hopper, which permits the escape of air from the measuring vessels, while the latter are being charged. This arrangement is of importance as the carrier prevents or impedes 50 a lateral escape of the air, which would interfere with a quick and uniform filling of the measuring vessels, were other means not provided. Bail 53 will during the rotation of shaft 50, withdraw from the material, the 55 support it obtains upon the face of the hopper, so that when a measuring vessel arrives beneath the latter, the material is left unsupported and is free to drop quickly and freely into the vessel.

60 I claim:

1. A machine of the character described, comprising a carrier, a plurality of measuring vessels, each measuring vessel being composed of an upper section secured to the 65 carrier, and a valve-controlled lower section

telescoping said upper section, a support for said lower section, a sleeve depending from said support, rods depending from the sleeve, levers pivotally connected to the rods, a threaded screw rod connected to the levers, 70 a second oppositely threaded screw rod, and a right and left nut engaging both screw rods.

2. A machine of the character described, comprising a carrier, open bottomed measuring vessels secured thereto, valves controlling the lower outlet ends of said vessels, arms, means for operatively connecting said arms to the valves, a roller carried by each arm, and a notched glideway engaged by the 75 roller.

3. A machine of the character described, comprising a carrier, open bottomed measuring vessels secured thereto, valves controlling the lower outlet ends of said vessels, 80 arms, means for operatively connecting said arms to the valves, a notched glideway, an adjustable notched ring in proximity to said glideway, and a roller on each arm adapted to simultaneously engage the glideway and 85 ring.

4. A machine of the character described, comprising a carrier, open bottomed measuring vessels secured thereto, valves controlling the lower outlet ends of said vessels, and a curved stripper arranged above the carrier and having a central section which is bent horizontally and lies above the path 90 of the measuring vessels.

5. A machine of the character described, comprising a carrier, open bottomed measuring vessels secured thereto, valves controlling the lower outlet ends of said vessels, a feed hopper arranged above the path of the vessels, a shaft centered within the hopper, and a tapering upright wing secured to said shaft and extending from the carrier to a point near the top of the hopper.

6. A machine of the character described, comprising a carrier, open bottomed measuring vessels secured thereto, valves controlling the lower outlet ends of said vessels, a feed hopper arranged above the path of the vessels, a shaft centered within the hopper, an upright tapering wing secured to the shaft, and a bail having an inclined shank that extends along the inner face of the hopper.

7. A machine of the character described, comprising a rotatable carrier, measuring vessels suspended therefrom, valves controlling said vessels, arms carried by the valves, a glideway having a notched section and engaged by said arms, and a funnel below the carrier.

8. A machine of the character described, comprising a rotatable carrier, measuring vessels suspended therefrom, valves controlling said vessels, arms carried by the valves, a glideway having a notched section and

engaged by the arms, a coöperating notched ring encompassed by the glideway and rotatable independently therefrom, and a hopper below the carrier.

5 9. A machine of the character described, comprising a rotatable carrier, measuring vessels suspended therefrom and composed of upper shells and telescoping lower shells, valves controlling the lower shells, arms car-

ried by the valves, a glideway engaged by the arms, and means for adjusting the lower shells and the glideway simultaneously in a vertical direction.
